(57) **CLAIM**

The ornamental design for a collapsible car trunk and grocery organizer with hard cover and cooler bag, as shown and described.

DESCRIPTION

FIG. 1 is a right side view of the organizer with three compartments, a cooler bag and straps, the organizer in an open condition showing my new design.

FIG. 2 is a top view thereof.

FIG. 3 is a side view thereof, wherein the organizer is in a collapsed state with two compartments.

FIG. 4 is another side view thereof, wherein the organizer is in a compressed state with one compartment.

FIG. 5 is a top view thereof, wherein the organizer with two compartments is shown in a collapsed state.

FIG. 6 is another top view thereof, wherein the organizer with one compartment is in a collapsed state.

FIG. 7 is a perspective view of the organizer, wherein the organizer is in a fully closed and collapsed state.

FIG. 8 is a front view thereof.

FIG. 9 is a rear view thereof.

FIG. 10 is a right side view thereof.

FIG. 11 is a left side view thereof.

FIG. 12 is a top view thereof.

FIG. 13 is a bottom view thereof.

FIG. 14 is a right side view thereof, wherein the top hard cover is installed.

FIG. 15 is a top view thereof.

FIG. 16 is a bottom view thereof; and,

FIG. 17 is another side view of the organizer with three compartments, a cooler bag and straps and wherein the organizer is in an opened state.
